UNITED STATES PATENT OFFICE.

AUGUST KNAUS, OF PHILADELPHIA, PENNSYLVANIA.

ARTICLE OF JEWELRY.

1,385,691.

Specification of Letters Patent. Patented July 26, 1921.

Application filed July 23, 1920. Serial No. 398,510.

To all whom it may concern:

Be it known that I, AUGUST KNAUS, a citizen of the United States, residing in the city and county of Philadelphia, State of Pennsylvania, have invented a new and useful Article of Jewelry, of which the following is a specification.

My invention consists of an article of jewelry such as a bar, brooch, shawl or lace pin, or the like, having a center or setting member composed of a frame having a jewel or ornament thereon whereby said frame with its jewel or ornament remaining thereon as a fixture may be removed and applied 10 interchangeably to other articles of jewelry such as a lavallière, a pendant, a stick pin, etc. provision being made for securing said center member to either article so as to be retained securely in position, the same jewel 15 or ornament with its frame thus being applicable to either of the other articles of jewelry.

The invention is satisfactorily illustrated in the accompanying drawing, but the important instrumentalities thereof may be varied, and so it is to be understood that the invention is not limited to the specific details shown and described, as long as they are within the spirit or scope of the claims. 20 Figure 1 represents a face view of a bar or bar pin, an article of jewelry embodying my invention.

Fig. 2 represents a rear or reverse view thereof.

Fig. 3 represents a rear view of the bar with the center embodying my invention.

Fig. 4 represents a rear elevation of the center.

Fig. 5 represents a longitudinal section 40 of a portion on line 5—5 Fig. 1, on an enlarged scale.

Fig. 6 represents a transverse section on line 6—6 Fig. 5.

Fig. 7 represents a rear view of a stick 45 pin embodying my invention.

Fig. 8 represents a face view of a lavallière embodying my invention.

Similar numerals of reference indicate 50 corresponding parts in the figures.

Referring to the drawings.

1 designates what is known as a bar or bar pin formed of a suitably shaped plate of metal with a center or setting 2 thereon, the latter comprising a frame with a jewel or 55 jewels or ornaments thereon as a fixture thereof, as well known in the art, said frame

having therein the opening 3 in whose wall 4, on opposite sides thereof are the recesses 5 and 6. On the inner or underside of the frame of the center or setting is the flange 60 7 which is adapted to enter the opening 3 and to fit against the wall 4 whereby turning of said frame and consequently of the center or setting is prevented.

Projecting angularly outwardly from one 65 side of said flange is the stud 8 which is adapted to enter the recess 5. On the side of said flange opposite to said stud is the bolt 9 which is adapted to enter the adjacent recess 6, said bolt being slidingly contained 70 in the barrel 10, which is secured to the underside of the frame of the center 2 and having therein the spring 11 which is adapted to force said bolt into said recess 6 and retain it therein. 75

The frame of the center has on its circumference the outturned rim 12 which is adapted to be seated on the portion of the pin 1 around the wall of the opening 3, thus sustaining the center steadily on the bar and 80 limiting its extent of entrance into said opening, it being seen that when the center is positioned and the stud 8 occupies the recess 5, and the bolt 9 occupies the recess 6, the center will be held firmly connected with 85 the pin.

The inner end of the bolt is provided with the knob or head 13 whereby the bolt may be conveniently drawn in preparatory to applying the center in position, it being seen that 90 the under portion of the center is presented to the opening 3 and partially entered therein and so manipulated that the stud 8 is inserted in the recess 5. Then the bolt 9 is drawn in or back and the center inserted to 95 full extent in the opening 3 when the bolt is let go and its nose or point portion enters the recess 6 and thus the center is connected at both of its ends with the bar.

In order to remove the center from the 100 bar, the bolt is drawn in or back whereby it leaves the recess 6 when the center may be partially raised and tilted and manipulated to withdraw the stud 8 from the recess 5 when the center is disconnected from the bar 105 and may be entirely removed from the opening 3 and consequently from the bar.

14 designates a lavallière, and 15 designates a stick pin which are equipped similarly to the bar 1 whereby the center as removed from the latter may be fitted to the 110 plate or pendant of the lavallière or to the

plate or head of the stick pin and held connected with either by the respective stud 8 and bolt 9 on said parts, it being seen that the center is thus interchangeable for different articles of jewelry and so may be worn with either while being held removable in position on the respective article.

The center is shown as set with jewels, but other ornaments may be employed, and it 10 may be enameled or otherwise faced as customary in the class.

Attention is directed to the fact that the jewel or ornament on the frame thereof is not designed to be removed from the same 15 but remains a fixture thereof and so the frame with its jewel or ornament is applicable to the various articles of jewelry, and thus the same jewel or ornament may render services on each of said articles, each being 20 provided with a registering opening 3 for the frame of the center, and the wall of said opening is equipped with the recesses 5 and 6 therein for the occupation of the angularly extending stud 8 and the bolt 9 therein 25 to hold the frame of the same center in position in either of the articles to which it is interchangeably applied.

Having thus described my invention what I claim as new and desire to secure by Letters Patent, is:—

1. In an article of jewelry of the character stated, a plate having therein an opening, and recesses in the wall thereof, and an in-

terchangeable center composed of a frame and an ornament fixed thereto, and means 35 on the inner side of said center adapted to connect the latter with said plate, said means consisting of members on said frame adapted to pass through said opening and enter said recesses.

2. An article of jewelry consisting of a plate having therein an opening and a removable center composed of a frame and an ornament fixed thereto, said center having 40 on its inner side a flange adapted to occupy 45 said opening, the wall of the latter having therein recesses, and means extending from said flange adapted to pass through said opening and enter said recesses and thereby retain the center removably in position on 50 said plate.

3. An article of jewelry of the character stated having a center which is removably mounted on a seating portion thereof, recesses in said portion, and a stud and a 55 spring pressed bolt respectively on said center, said bolt and stud being adapted to enter said recesses and thereby retain the center steadily and firmly in place, and adapted to permit the convenient removal of the center 60 from said article.

AUGUST KNAUS.
